Primary Examiner — Michelle E. Wilson*Assistant Examiner* — Clesse Moore, Jr.(74) *Attorney, Agent, or Firm* — Bay State IP, LLC(57) **CLAIM**

The ornamental design for a vehicle tire traction device for mud, sand and snow, as shown and described.

DESCRIPTION

FIG. 1 is a front perspective view of the vehicle tire traction device for mud, sand and snow showing my new design;

FIG. 2 is a front view thereof;

FIG. 3 is a back view thereof;

FIG. 4 is a left side view thereof;

FIG. 5 is a right view thereof;

FIG. 6 is a top view thereof;

FIG. 7 is an upward view thereof; and,

FIG. 8 is an environment view of the vehicle tire traction device for mud, sand and snow in use on a tire.

The broken lines are included for the purpose of showing the vehicle tire traction device for mud, sand and snow in an environment on a tire and the tire and forms no part of the claimed design.

1 Claim, 8 Drawing Sheets(56)
